UNITED STATES PATENT OFFICE.

HERBERT S. VALENTINE, OF READING, PENNSYLVANIA, ASSIGNOR TO READING CRANE & HOIST WORKS, OF READING, PENNSYLVANIA.

DESIGN FOR A MOTOR-CASING FOR ELECTRIC HOISTS.

43,066.

Specification for Design.

Patented Sept. 24, 1912.

Application filed June 28, 1912. Serial No. 706,496. Term of patent 14 years.

To all whom it may concern:

Be it known that I, HERBERT S. VALENTINE, citizen of the United States, residing at Reading, Berks county, State of Pennsylvania, have invented a new, original, and ornamental Design for Motor-Casings for Electric Hoists, of which the following is a specification, reference being had to the accompanying drawing, forming a part thereof.

In the drawing:—Figure 1 is a side eleva-

tion, Fig. 2 is a plan view, and, Fig. 3 is an end elevation, of a motor casing for electric hoists, showing my design.

I claim:—

The ornamental design for a motor casing for electric hoists, as shown.

HERBERT S. VALENTINE.
